INVENTOR.

UNITED STATES PATENT OFFICE.

GEORGE W. DOVER, OF CRANSTON, RHODE ISLAND.

PIN.

SPECIFICATION forming part of Letters Patent No. 729,557, dated June 2, 1903.

Application filed December 5, 1902. Serial No. 133,993. (No model.)

To all whom it may concern:

Be it known that I, GEORGE W. DOVER, a citizen of the United States, residing at Cranston, in the county of Providence and State 5 of Rhode Island, have invented certain new and useful Improvements in Pins, of which the following is a specification.

My invention relates to brooches and other pins, and has for its main objects strength, 10 cheapness, and simplicity. These are attained by the improved structure of both the pin-tongue and the housing or joint, as will be hereinafter set forth, and shown in the accompanying drawings, wherein—

15 Figures 1, 2, 3, 4, 5 are side elevations of the pin-tongue in its various stages of completion; Fig. 6, a plan of the housing-blank; Figs. 7, 8, 9, side, edge, and plan views, respectively, of the housing-blank bent into final position. 20 Fig. 10 is a perspective view of a modification of the invention, and Fig. 11 a central longitudinal section of the same.

Like letters of reference indicate like parts throughout the views.

25 The novel pin-tongue is formed from an ordinary pin-tongue blank *a*, Fig. 1, by swaging the blunt end thereof into a spherical head *b*, as shown in Fig. 2. The head is then flattened and centrally pierced *c*, Fig. 3. A 30 portion of this circular flattened head is cut away to form a peripheral shoulder or projection *d*, Fig. 4. An edge view of the completed tongue is shown in Fig. 5.

Referring now to the housing or cup portion of my pin, it is herein sought to avoid 35 the weaknesses inherent in prior forms, which provide a support for the tongue forward the pivot. A familiar method is to form this support or bearing by upwardly bending from 40 the base of the housing a tongue, which after slight use collapses and is forced downwardly and away from the remainder of the housing under the vertical pressure of the pin-tongue upon its upper margin. In my structure this 45 weakness is overcome by transverse walls integral with one of the housing sides. The details are as follows: From a flat metallic sheet is cut a blank with the outline shown in Fig. 6. The blank consists of an oblong 50 strip *e i h*, with openings *o* centrally located near each extremity. From both sides of the upper portion *e* of the strip project wings *g f*,

having concaved upper margins; but one or both margins may be straight, if desired. The cup or housing is completed by bending the 55 parts as follows: The portion *i* forms the base of the cup, and upwardly from this is bent in parallel planes the portions *e* and *h* of the blank forming the side walls of the housing or cup. The wings *g* and *f* of the blank are 60 bent inwardly into parallel planes at right angles to the planes of the side walls, thus completing the housing. A pivot *l* traverses the openings *o* in the walls and the 65 opening *c* in the pin-tongue, the latter being mounted upon the pivot intermediate the walls *e* and *h*, with the shoulder *d* above the pivot. The base *i* of the housing is fixed to the pin-body *j* in the usual manner, and the latter has the usual catch *k*.

In Fig. 10 the housing is shown without a front wall.

In operation it will be noted that the top of the wall *g* forms a bearing for the pin-tongue shaft when the latter is in engagement with the catch, while the upper margin of the rear wall *f*, in conjunction with the shoulder *d*, furnishes a limit to the backward travel of the tongue *a*.

What I claim as new is—

1. In a pin, the combination with a tongue having a head, a shoulder upon the head, a pivot traversing the head, housing-walls in which the pivot is mounted, and means intermediate the walls for intercepting the shoulder when the tongue is raised.

2. In a pin, the combination with the tongue of a flat head upon its extremity, a shoulder upon the head, a pivot traversing the head, housing-walls in which the pivot is mounted and a rear housing-wall against which the shoulder is adapted to contact in its travel.

3. As a new article of manufacture, a housing comprising a base, side walls rising from said base, and a wing integral with one of the side walls and bent inwardly at right angles thereto.

4. In a pin, the combination with the tongue having a flat head upon its extremity, a shoulder upon the head, a pivot traversing the head, housing-walls in which the pivot is mounted, and a housing-wall against which the shoulder is adapted to contact when the tongue is raised.

5. In a pin of the class described, a bearing, a fixed stop member, and the pin-tongue having a perforated flattened head pivoted to the bearing and having a shoulder on said head for engagement with said fixed stop member when said pin is raised.
6. A pin-tongue, a bearing therefor, said pin comprising a shaft and a perforated flattened head, a shoulder formed on said head, said shoulder engaging said bearing when the pin is raised.
7. A pin-tongue, a housing therefor, said

housing comprising a base portion, side walls provided with bearings for the pin and bent at right angles to said base portion, and a wing integral with a side wall and bent at right angles thereto.

In testimony whereof I have affixed my signature in presence of two witnesses.

GEORGE W. DOVER.
